A. CLEMENSEN

TAPPET NOISE ELIMINATOR

Filed Jan. 22, 1927

UNITED STATES PATENT OFFICE.

AXEL CLEMENSEN, OF CHICAGO, ILLINOIS.

TAPPET-NOISE ELIMINATOR.

Application filed January 22, 1927. Serial No. 162,709.

This invention relates to an internal combustion engine and more particularly to an improved mechanism associated with an engine valve mechanism for the purpose of 5 eliminating or reducing the noise ordinarily produced by loose tappets.

It is an object of this invention to provide a tappet noise eliminator for use in connection with internal combustion engines, said 10 noise eliminator mechanism being associated with the valve stem and mainly comprising concentric sleeves constructed of different metals and having different coefficients of expansion whereby the tappet adjustment screw 15 is adapted to be set to contact the lower end of one of said sleeves to eliminate clearance, thereby reducing tappet noise to a minimum.

It is an important object of this invention to provide an internal combustion engine 20 valve or tappet mechanism with expansible metal sleeves having different coefficients of expansion and with superimposed friction springs adapted to maintain the contact between the valve mechanism and the tappet to 25 reduce tappet noise, thereby producing a quiet running engine.

Other and further important objects of this invention will be apparent from the disclosures in the specification and the accompanying 30 drawings.

This invention (in a preferred form) is illustrated in the drawings and hereinafter more fully described.

On the drawings:

35 Figure 1 is an enlarged fragmentary vertical section view of an internal combustion engine illustrating a valve and tappet mechanism embodying the principles of this invention with parts shown in elevation and with 40 the operation illustrated in dotted lines.

Figure 2 is a transverse detail section taken on line II—II of Figure 1.

Figure 3 illustrates a vertical section through a tappet mechanism embodying the 45 principles of this invention and having associated therewith a standard valve mechanism, a fragmentary portion of which is illustrated.

As shown on the drawings:

The reference numeral 1 indicates a cylinder 50 of an internal combustion engine casting which has integrally formed thereon a valve cage 2 and a water jacket 3 above a horizontal partition or bracket 4 which forms a part of the casting or the top wall of the crank case 5.

The bracket 4 is provided with a passage in 55 which a valve tappet 6 is slidably mounted with the tappet head 7 engaged by a cam 8 mounted on the engine cam shaft 9. The tappet is provided with an adjustment nut or screw 10 adapted to be held in an adjusted 60 position by means of a lock nut 11.

Coacting with a valve seat 12 formed in the valve cage 2 is a valve head 13 having a valve stem 14 which projects downwardly and terminates in a flange or disk 15. The valve stem 14 projects axially through an inner valve sleeve 16 constructed of a metal having a high coefficient of expansion. The lower end of the inner sleeve 16 is held seated against the valve disk 15 by means of an 70 axially passaged retaining cap 17 through which the valve stem 14 also projects. The reduced threaded portion of the cap 17 is threaded in the upper threaded end of an outer valve sleeve 18 constructed of a different kind of metal from the sleeve 16 and having a low coefficient of expansion. The lower end of the outer valve sleeve 18 is closed and is adapted to be contacted by the tappet adjustment screw 10, thereby eliminating tappet 75 clearance. The closed end of the outer valve sleeve 18 affords a pocket below the valve disk 15, said pocket having positioned therein a plurality of arced friction plate springs 19 which normally act to hold the valve disk 15 80 resiliently against the lower end of the inner sleeve 16. The outer valve sleeve 18 projects through a valve stem guide 20 which is integrally formed on the casting 1 below the valve cage 2. Engaged around the valve stem 90 guide 20 is the upper end of a coiled valve spring 21 which is coiled around the outer valve sleeve 18 and has the lower end thereof seated in a groove provided in the upper face of a stop plate or disk 22 which is slidably 95 engaged around the lower portion of the outer sleeve 18 and resiliently seats against a stop ring 23 engaged within a peripheral groove formed in the lower portion of the outer sleeve 18. The coiled spring 21 thus acts to resiliently hold the valve sleeves in their lowermost position with the valve head 13 seated in the valve seat 12.

To eliminate clearance between the lower closed end of the outer valve sleeve 18 and the tappet mechanism, the tappet lock nut 11 is loosened and tappet adjustment screw 10 is set to contact the lower end of the outer sleeve 18.

The lock nut is then turned into a locking position to hold the tappet adjusted.

The tappet noise is reduced due to the peculiar arrangement of the two concentric valve sleeves 16 and 18 which are constructed of different kinds of metal with the inner sleeve 16 being constructed of a metal having a high coefficient of expansion, so that when the sleeves 16 and 18 become heated the inner sleeve 16 will expand an amount greater than the amount of expansion of the outer sleeve 18. By heating the valve and tappet mechanisms the valve stem 14, which is constructed of the same metal as the outer sleeve 18, expands downwardly from the valve seat 12, thereby causing the friction plate springs 19 to be compressed an amount sufficient to allow for the expansion of the valve stem. The amount of expansion of the inner sleeve 16 is greater than the expansion of the valve stem 14 and the outer sleeve 18, permitting the inner sleeve not only to expand downwardly to compensate for the downward expansion of the valve stem 14, but is also permitted to expand upwardly with the outer sleeve 18 into the dotted line position shown in Figure 1, thereby producing an arrangement wherein the lower end of the outer sleeve 18 is maintained in the same position, being contacted by the tappet adjustment screw to maintain the various tappet and valve parts in their proper working relation without any tappet clearance to produce a substantially noiseless engine as far as tappet noise is concerned.

Figure 3 illustrates a modified form of the invention in which the improved mechanisms are associated with the tappet mechanism of an internal combustion engine instead of with the valve mechanism. In this form of the device the reference numeral 24 indicates a standard valve stem provided with a coiled control spring 25. The lower end of the valve stem is in contact with the head of a valve tappet adjusting screw 26 provided with a check nut 27. The adjusting screw 26 is threaded into the upper end of an inner tappet sleeve 28 the upper end of which is provided with a flange 29 against which the check nut is adapted to seat. The lower end of the inner tappet sleeve 28 is closed by means of a flanged head 29 which is slidably engaged in an outer tappet sleeve 30 constructed of a metal having a low coefficient of expansion. The lower end of the outer tappet sleeve 30 is closed by means of a tappet head 31 with which a lifter cam 32 is positioned to coact. The outer tappet sleeve 30 is slidably mounted in a tappet guide bracket 33 forming a part of the casting of an internal combustion engine. Seated in the lower closed end of the outer tappet sleeve 30 are a plurality of arched friction plate springs 34 superimposed on one another, with the uppermost spring in contact with the middle portion of the head 29 of the inner tappet sleeve. Engaged

around the inner tappet sleeve 28 is an intermediate tappet sleeve 35 constructed of a metal having a high coefficient of expansion. The lower end of the intermediate tappet sleeve 35 rests upon the flanged head 29 of the inner tappet sleeve 28. Engaged around the upper portion of the inner tappet sleeve 28 below the flange 29 is an axially passaged retaining cap or collar 36 having a reduced exteriorly threaded portion which is threaded into the upper interiorly threaded end of the outer tappet sleeve 30. The inner end of the retaining cap 36 is in contact with the upper end of the intermediate tappet sleeve 35.

In the form of the device illustrated in Figure 3 the tappet noise is adapted to be reduced due to the peculiar arrangement of the concentric tappet sleeves 30 and 35 which are constructed of different kinds of metal, with the sleeve 35 being constructed of a metal having a high coefficient of expansion so that when the sleeves 30 and 35 become heated the inner sleeve 35 will expand an amount greater than the amount of expansion of the outer tappet sleeve 30. The inner tappet sleeve 28 is constructed of the same metal as the outer tappet sleeve 30 so that when the valve and tappet mechanisms become heated the inner tappet sleeve 28 expands downwardly, thereby causing the friction plate springs 34 to be compressed an amount sufficient to allow for the expansion of said inner tappet sleeve. Inasmuch as the amount of expansion of the intermediate tappet sleeve 35 is greater than the expansion of the inner tappet sleeve 28 and the outer tappet sleeve 30 the intermediate tappet sleeve 35 is permitted not only to expand downwardly to compensate for the downward expansion of the inner valve sleeve 28, but is also permitted to expand upwardly, with the outer sleeve 30 affording an arrangement whereby the upper end of the outer tappet sleeve 30 is maintained in the same position to maintain the various tappet and valve parts in their proper working relation without any tappet clearance, thereby producing a substantially noiseless engine as far as tappet noise is concerned.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. The combination with an internal combustion engine and a tappet mechanism thereof, of a valve, a valve stem formed thereon, a disk formed on the lower end of said valve stem, an inner sleeve surrounding the valve stem and resting on said disk, an outer sleeve surrounding said inner sleeve with the lower end of said outer sleeve closed and in contact with said tappet mechanism,

a plurality of superimposed friction plate springs in the lower end of said outer sleeve below said valve stem disk, a stop ring recessed into the outer periphery of said outer sleeve, a stop plate engaged on said outer sleeve above said stop ring, and a coiled spring engaged around said outer sleeve and seated against said stop plate.

2. The combination with an engine valve cage having a valve seat formed therein, of a valve head adapted to seat on said valve seat, a guide integrally formed on said valve cage, a stem on said valve head, a disk formed on the lower end of said valve stem, an adjustable tappet mechanism, an inner sleeve surrounding said valve stem and seated on said disk, said inner sleeve having a high coefficient of expansion, an outer sleeve surrounding said inner sleeve and having a low coefficient of expansion, said outer sleeve being closed at its lower end and in contact with the tappet mechanism to eliminate clearance, plate springs in said outer sleeve below the valve stem disk, a cap surrounding said valve stem and engaged in the upper end of said outer sleeve to contact the upper end of said inner sleeve, stop members mounted on the lower end of said outer sleeve, and a valve control spring engaged around said outer sleeve with the lower end of said spring engaging said stop members and the upper end of said spring engaged around said guide.

3. The combination with an engine casting, of a tappet mechanism mounted thereon, a valve, a valve stem formed thereon, a disk on the lower end of said valve stem, an inner sleeve surrounding the valve stem and contacting said disk, an outer sleeve surrounding said inner sleeve with the outer sleeve closed at its lower end and contacting said tappet mechanism, spring members positioned in the outer sleeve below the valve stem disk, a cap engaged in the upper end of said outer sleeve and contacting said inner sleeve, and a spring mounted on said outer sleeve for normally holding the valve in closed position.

4. The combination with an engine casting and a valve seat formed therein, of a valve adapted to seat in said valve seat, a stem on said valve, a plurality of concentric sleeves on said valve stem with said sleeves constructed of different kinds of metal having different coefficients of expansion, spring members in said outer sleeve below the valve stem, means connecting the upper ends of said concentric sleeves, a tappet mechanism, adjustable means forming a part thereof adapted to be set in contact with the outer one of said sleeves to eliminate clearance, stop members on said outer sleeve, and a spring engaged around said outer sleeve and seated against said stop members.

5. The combination with an adjustable en-

gine tappet mechanism, of a valve, a valve seat therefor, a stem formed on said valve, a disk on the lower end of said valve stem, an inner sleeve surrounding said valve stem constructed of a metal having a high coefficient of expansion, an outer sleeve surrounding said inner sleeve constructed of a metal having a low coefficient of expansion, said outer sleeve being closed at its lower end and contacted by said tappet mechanism, spring members in said outer sleeve below the valve stem disk, a closure for the upper end of said outer sleeve with said closure contacting the upper end of said inner sleeve, a stop mounted on said outer sleeve, and a valve control spring engaged around said outer sleeve and contacting said stop.

6. The combination with an engine tappet mechanism and a valve mechanism, of a plurality of concentric sleeves constructed of different kinds of metal having different coefficients of expansion, said sleeves being carried by the valve mechanism, spring members between said sleeves and said valve mechanism, and a control spring for the valve mechanism engaged around said concentric sleeves.

7. The combination with a valve seat and valve, of an adjustable tappet mechanism, a plurality of concentric sleeves carried by the valve with one of said sleeves being in contact with the tappet mechanism and having a coefficient of expansion less than the coefficient of expansion of the other sleeve, spring members between said valve mechanism and said sleeves, and a control spring engaged around said sleeves for normally holding the valve on said valve seat.

8. A tappet noise eliminator mechanism comprising an engine tappet, a valve cage having a valve seat formed therein, a valve mechanism for coaction with said valve seat, a plurality of concentric sleeves carried by the valve mechanism with said sleeves constructed of different kinds of metal having different coefficients of expansion, springs positioned between said sleeves and said valve mechanism, and a control spring surrounding said sleeves for normally holding the valve engaged in said valve seat.

9. The combination with an engine tappet mechanism of a valve mechanism, a plurality of concentric sleeves carried by said valve mechanism with said sleeves constructed of different kinds of metal having different coefficients of expansion, said tappet mechanism being normally set to eliminate clearance between the tappet mechanism and said concentric sleeve, and resilient means carried by said concentric sleeves to assist the same in contacting said tappet mechanism.

10. The combination with a tappet mechanism, of a valve mechanism, and expandible members having different coefficients of expansion carried on the valve mechanism adapted to permit said mechanisms to be

mounted without clearance to obviate tappet noise.

11. The combination with a tappet mechanism, of a valve mechanism, expandible members associated with one of said mechanisms with said members having different coefficients of expansion, and spring means carried by said expandible members; said expandible

members and spring means permitting the tappet mechanism and said valve mechanism to be mounted in contacting relation to obviate clearance and tappet noise.

In testimony whereof I have hereunto subscribed my name at Chicago, Cook County, Illinois.

AXEL CLEMENSEN.
